CAGE ASSEMBLY FOR CRYSTALS

Arthur W. Ziegler, Short Hills, N. J., assignor to
 Bell Telephone Laboratories, Incorporated, New
 York, N. Y., a corporation of New York

Application January 10, 1950, Serial No. 137,690

4 Claims. (Cl. 171—327)

1

This invention relates to the manufacture of crystals and more particularly to means and methods for assembling and mounting piezoelectric crystal units.

It is common practice in the piezoelectric crystal art to mount crystals by means of resilient wires cemented or soldered to the crystal surface and in turn supported by structural members, the entire assembly being enclosed within a sealed envelope. The structural members, which may be slender rods or tubes of nickel or an equivalent material, should be susceptible of being formed to close tolerances and have high conductivity so that electrical connection to the crystal may be made therethrough. The rods are held in a spaced array, commonly called a cage, as by end spacers of mica or equivalent material. Metal eyelets or grommets are fixed in the spacers to receive the rods, which may be secured thereto by spot welding or similar means.

Various considerations relating to operating characteristics of the crystals have led to the use of fine resilient wires which may be of the order of a few thousandths of an inch in thickness, for supporting the crystal on the rods. The mass of the piezoelectric crystal is sufficient so that a severe mechanical shock, such as that experienced if a crystal unit is dropped, may cause separation at the bond between the crystal and the supporting wires, or a permanent displacement of the crystal position. The result may be the introduction of mechanical strains between the crystal and its support which will cause the crystal to vibrate at frequencies other than the period for which it was intended.

To avoid such consequences, it has been the practice to prevent excessive displacement of the crystal by means of bumpers. The bumpers may take the form of mica end plates which are apertured to permit the insertion of a portion of the crystal. The apertures are made sufficiently large so that the crystal in normal vibration will not come in contact with the mica spacer, but small enough to prevent crystal displacement during rough handling sufficient to produce the ill effects described above.

This spacing problem in practice has meant that each different type of crystal has required a set of mica spacers individually designed for its accommodation. This in turn entailed a requirement that a large number of small piece parts had to be kept on hand by the factory, which could neither be produced nor handled on a mass production basis. In addition, the assembly required the use by the factory operator of shims to align the crystal properly with the mounting

2

cage. This is a laborious and time consuming procedure and frequently results when improperly done in introducing strains into the supporting wires which would be reflected in operational failures and frequency inaccuracies.

An additional factor is the tendency of the softer synthetic materials, such as ethylene diamine tartrate, commonly known as EDT, to fracture easily on impact. Although the mica and polyethylene fluoride or "teflon" combination commonly used for the end spacers with synthetic crystals is relatively soft, it has been found that particles from the crystal surface may be broken off by repeated contacts with the teflon after displacement of the crystal from its normal position. This result has even obtained with the harder piezoelectric materials such as quartz, in spite of the comparative softness of all the mica bumper material there used.

10 The present invention eliminates the difficulties referred to above by providing a metal-to-metal bumper contact in a form which permits free floating mounting during the assembly of the crystal unit. In a crystal unit constructed 15 in accordance with the invention, bumper rods are secured to each end of the crystal. The mica spacers forming the cage ends are provided with bumper tubes of internal diameter substantially greater than that of the external diameter of the bumper rods. Thus, if displacement of the crystal occurs, it will be limited by the contact of the metal bumper rod with the metal bumper tube. The rods are so located on the crystal that they do not interfere with its electrical characteristics, once the initial adjustment for frequency has 30 been made during manufacture. The size of the rods is kept to a minimum consistent with ability to restrain the crystal during displacements. Hence, they exert a minimum effect on the crystal vibratory characteristics.

35 The invention comprehends in addition to the particular bumper system, a method of caging the crystal which is adapted to prevent the setting up of strains in the supporting assembly and 40 to aid in the accurate alignment of the crystal within its cage.

45 It will thus be seen that a primary object of the invention is to provide an improved crystal supporting system, and means and a method for 50 the free floating mounting of the crystal within the improved system.

Another object is the elimination of frequency variations resulting from the dislodging of minute particles of the crystal by contact with the bumper.

A further object is the elimination of strains in the mounting wires for a crystal unit.

A still further object is the improvement of the technique of assembling bumperized piezoelectric crystal units.

Yet another object is the improvement of crystal unit production by the elimination of an excessive number of individually dimensioned piece parts.

An additional object is the elimination of the necessity for laborious shimming operations in aligning the crystal within its cage.

A still further object is the provision of a method and tools for accomplishing a rapid assembly of free floating accurately aligned crystal units.

These and other objects may be achieved by the use of the embodiments illustrated, but it is to be understood that the embodiments as shown are exemplary only, and are intended to be the subject of such variations in form and shape and substitutions of materials as may be desirable to accomplish the objects of the invention.

The invention will be better understood by reference to the drawings in which:

Fig. 1 is a perspective view of a crystal unit embodying the bumper system of the invention, portions of the unit being broken away to illustrate some of the details with greater clarity;

Fig. 2 is a perspective view to an enlarged scale showing details of construction of a tool for use in the assembling process;

Fig. 3 is a fragmentary view showing details of the bumper system;

Fig. 4 is a view, partially in section, illustrating the first stage in a preferred method of caging a crystal;

Fig. 5 is a view partially in section showing another stage in the caging operation applicable to the method of which the first stage is illustrated in Fig. 4 and to another preferred method of caging; and

Fig. 6 shows the final stage of the completed caging operation arrived at by either of the preferred methods of caging described.

The invention as it is incorporated in a unit 45 designed for use with elongated rectangular piezoelectric crystals supported by resilient wires secured to the crystals near their longitudinal mid-points is shown in Fig. 1. A sealed crystal unit, generally designated as 1, includes in addition to a cage structure, a base 2 and a glass or metal envelope 4 secured thereto. Connecting terminals 5 extend through the base 2 of the envelope 4, and are joined to connecting leads 6 which are sealed through the press 7 of the envelope. Within the envelope, connecting leads 6 are bent to form supports for the "straights," or upright connecting and supporting cage rods 9, which are made of any readily formed, substantially rigid supporting material having good electrical conductivity, such as nickel. To the rods 9 are fixed, by means such as soldering at 10 or other conventional arrangements, resilient supporting wires 11. Supporting wires 11, which may be of the order of a few mils in diameter, 65 may be provided with quarter wave solder balls 12, to prevent the transmission through support wires 11 to the cage support rods 9 of energy from the crystal 14. Crystal 14 is secured to the support wires 11 by conventional means, such as 70 soldering to silver paste spots or by special adhesive attachments. The connection may also be made by the use of the headed wire technique when it is desired to secure a greater contact area with the crystal.

The crystal 14 has been shown as having substantial mass, and a single electrode coating area on each major face. Hence, four cage support rods 9 have been provided, with two support wires 11 joined to each side of the crystal. Many of the crystals used with mountings of this type have split or divided coatings, that is, there is a separation between portions of the coating covering a major face of the crystal, with separate connections between each of the coating portions and the remainder of the electrical circuit. Crystals embodying such divided platings are shown in Figs. 4 to 6, inclusive, where the central longitudinal type of division is illustrated. Other types of split coating arrangements may require different arrangements of the supporting wires, but it is to be understood that such variations are contemplated by the present invention.

The cage rods 9 are maintained in a fixed position by virtue of being fixed through upper and lower mica end spacers 16 and 17, respectively. A convenient method for thus securing the rods and mica spacers in the cage assembly, generally denominated as 19, involves the use of grommets or eyelets 20 which may be set fixedly into the mica spacers 16 and 17. Rods 9 may be secured to grommets 20 by spot welds 21, soldering or equivalent means.

Centrally of the upper and lower mica end spacers 16 and 17, there is disposed a bushing 22, in which are fixed upper and lower bumper tubes 23 and 24, respectively. Bumper rods 25 are secured to the center of each end of the crystal 14 by any means which will not interfere with the vibrational characteristics of the crystal. When used with synthetic crystals such as EDT for example, the bumper rods 25 may be fixed in the end of the crystal, or cemented to the crystal by conventional techniques.

In case the crystal is relatively thin, the area of attachment might overlap a small portion of the sides of the crystal for greater mechanical strength, being careful to remove enough of the electrode coating to avoid short-circuiting the separate electrode areas. The bumper rods 25 are of a diameter substantially less than the inner diameter of the bumper tubes 23 and 24, so that in ordinary operation there will be no contact between the bumper rods and the bumper tubes.

The inside diameter of the bumper tubes 23 and 24 should not be so great, however, that in "floating" the crystal, the points of attachment 37 of the rods to the crystal might enter the bumper tubes and permit contact between the tube and the crystal plate. The bumper rod 25 will, in a properly adjusted crystal unit, be centered in, but spaced from the bumper tube as best seen in the enlarged view of Fig. 3. Rods 25 should be just long enough so that they will not disengage from the bumper tubes 23 and 24 when maximum axial movement occurs.

The method of floating or aligning the crystal properly in the cage to produce the finished cage assembly 19 as seen in Fig. 6 involves the use of auxiliary tools. One of such tools is shown in Fig. 2 and its use will be discussed in connection with the methods of caging the crystal, which are a part of the present invention.

Previous methods of caging have required individual treatment for each size and type of bumperized unit, because of the many variations in width, thickness and length of the crystals involved. The improved method here described permits caging a wide range of crystal

sizes in a single size of cage, and making the entire adjustment in the spacing of the bumper tubes.

The first step is the production of the cage structure indicated generally as 19. Rods 9 are inserted into the eyelets or grommets 20 fixed in mica end spaces 16 and 17, as shown in the upper portion of Fig. 4. Fig. 4 shows the general relation of the parts prior to final assembly and it is to be understood that in the actual assembly of the cage 19, the crystal 14 is not present in the initial step. Grommets 20 are then spot welded or crimped securely to the rods 9 to form the cage assembly 19, in substantially the position shown in Fig. 5.

The next step in the production of the cage structure is the insertion of bumper tubes 23 and 24 in bushings 22 of both upper and lower mica spacers 16 and 17, the general practice being thereafter to solder one of the bumper tubes, usually the lower one to the bushing. Following this, the two floating tools 26 are inserted in these bumper tubes. These tools each consist of a shaft 27 on which is mounted a head 29. The position of the head 29 axially of shaft 27 is adjustable under the control of set screw 30. The shaft 27 is of such a diameter as to fit smoothly within one of the bumper tubes. After the insertion of these tools, a resilient locking pin 35 is arranged to snap into the transverse locking groove 34 at the end of shaft 27. The head 29 is then adjusted so that no play exists between the tools and their respective bumper tubes. It is seen that the locking pin prevents the bumper tubes 23 and 24 from falling out of bushings 22 during further handling of the cage.

A crystal 14 is then placed in the cage so that the bumper rods 25 may be inserted into the central bores 32 of the upper and lower floating tools 26. A tapered mouth portion 33 of shafts 27 of the floating tools assists in guiding the bumper rods 25 into their seating position. The alignment of the parts will then be as shown in Fig. 5 with the bumper tubes being pushed toward the crystal as far as they will go. If one of the bumper tubes has already been fixed into position in bushing 22, as is the usual practice only one bumper tube is pushed at this time and in this manner toward the crystal and soldered or otherwise fixed in place. Crystal support wires 11 are then soldered or otherwise secured to cage rods 9 as shown at 10 being careful that no stresses are introduced into the supporting wires 11 during the process by metallic contact between wires 11 and rods 9, other than that through the solder joint cast therearound. The locking pins 35 are removed and thereafter the shafts 27 from the bumper tubes 23 and 24. The crystal is then fully floated in its cage.

An alternative production method, for use in those cases where the variation in the length of crystals to be caged is in excess of three-fourths of an inch, is to proceed as shown in Fig. 4 by fixing the upper mica spacer 16 to the cage rods 9 after the insertion of the crystal, and making the final accommodation for different crystal lengths through adjustment of the position of one or both of the bumper tubes.

While the invention has been illustrated to include the use of a bumper tube inserted in a bushing or grommet 22 in the mica end spacers as illustrated at 23 and 24, a variation of the alternative caging method is possible in which the tube is omitted. In such cases, the bushing

or eyelet 22 itself functions as the bumper tube. Fig. 3 illustrates such a variation and shows in detail the relative proportions of the bumper rod 25 and the grommet 22 which acts as the bumper tube.

As an alternative construction, it will also be seen that the relations of the bumper rods and tubes may be reversed. That is, the rods may be secured to the mica end spacers, and bumper tubes, or the equivalent in the form of metallized bores, set into the ends of the crystal.

It will thus be seen that the invention provides a simple and effective method for caging crystals, and for aligning them accurately relative to a bumper system having improved characteristics, during their assembly. It allows a single cage to be used with a wide assortment of sizes of crystals, in place of the many individual parts hitherto required to be handled during the caging operation.

What is claimed is:

1. In combination with a piezoelectric crystal unit having a plurality of supporting rods held in alignment by upper and lower insulating spacing disks and a piezoelectric crystal supported by resilient lead wires fixed to said rods, means for limiting displacements of said crystal, comprising a lower tubular bumper member fixed to said lower disk, an upper tubular bumper member fixed to said upper disk in axial alignment with said first tubular member, and guide members of transverse dimensions substantially less than the internal diameter of said tubes fixed in axial alignment to each end of said crystal and extending into said tubes.

2. In combination with a piezoelectric crystal unit having a plurality of supporting rods held in alignment by upper and lower insulating spacing disks, and a piezoelectric crystal supported by resilient lead wires fixed to said rods, means for preventing excessive displacement of said crystal, comprising a pair of hollow members fixed to said disks in axial alignment, and axially aligned members of transverse dimensions substantially less than the inside dimensions of said hollow members fixed at opposite ends of said crystal and extending into said hollow members.

3. In combination with a piezoelectric crystal unit having a plurality of supporting rods held in alignment by upper and lower insulating spacing disks, and a piezoelectric crystal supported between said disks by resilient lead wires fixed to said rods, a bumper system, comprising a lower bumper tube fixed to said lower insulating spacing disk, an upper bumper tube fixed to said upper insulating spacing disk in axial alignment with said short bumper tube, and bumper rods fixed in axial alignment to opposite ends of said crystal and extending freely into said bumper tubes.

4. In combination with a piezoelectric crystal unit having a plurality of supporting rods held in alignment by upper and lower insulating spacing disks, and a piezoelectric crystal supported by resilient lead wires fixed to said rods, bushing members fixed in said upper and lower disks in axial alignment, tubes extending through said bushing members, and rods of substantially smaller diameter than the inner diameter of said tubes fixed terminally in said crystal and extending therefrom into said tubes.

ARTHUR W. ZIEGLER.
